(57) **CLAIM**

The ornamental design for an automotive tire wheel, as shown and described.

DESCRIPTION

FIG. 1 is a perspective view of the automotive tire wheel of this application;

FIG. 2 is a front view thereof;

FIG. 3 is a rear view thereof;

FIG. 4 is a top view thereof;

FIG. 5 is a bottom view thereof;

FIG. 6 is a right side view thereof; the left side view being a mirror image thereof;

FIG. 7 is a cross-sectional view thereof taken along line 7—7 of FIG. 2;

FIG. 8 is a front view thereof; and,

FIG. 9 is a cross-sectional view of a spoke of the wheel taken along lines 9—9 of FIG. 8.

The broken line showing of environment is for illustrative purposes only and forms no part of the claimed design.
